[57] CLAIM

The ornamental design for a stapler, as shown and described.

DESCRIPTION

FIG. 1 is a perspective view of one embodiment of the stapler showing our new design;

FIG. 2 is a top view thereof;

FIG. 3 is a bottom view thereof;

FIG. 4 is a side elevational view thereof;

FIG. 5 is an opposite side elevational view;

FIG. 6 is a front elevational view thereof;

FIG. 7 is a rear elevational view thereof;

FIG. 8 is perspective view of another embodiment of the stapler showing our new design;

FIG. 9 is a top view thereof;

FIG. 10 is a bottom view thereof;

FIG. 11 is a side elevational view thereof;

FIG. 12 is an opposite side elevational view;

FIG. 13 is a front elevational view thereof; and,

FIG. 14 is a rear elevational view thereof.

The surface shading shown in the embodiment of FIGS. 8-14 indicates the contrast between the colors used in the design of the stapler.

The broken lines shown on the inside of bottom portion of the stapler in FIGS. 1, 4 & 5 of one embodiment and FIG. 8 of another embodiment define the bounds of the claimed design and form no part thereof.
